MINEHEART BRUNELL, OF ALLEGANY, NEW YORK, ASSIGNOR OF ONE-HALF
TO PHILOPENE BRUNELL, PETER J. FURNACE, VICTOR A. FURNACE, AND
PHILIP HYDE, ALL OF SAME PLACE.

COMPOUND STEAM-ENGINE.

SPECIFICATION forming part of Letters Patent No. 289,065, dated November 27, 1883.

Application filed August 26, 1883. (No model.)

To all whom it may concern:

Be it known that I, MINEHEART BRUNELL, of Allegany, in the county of Cattaraugus and State of New York, have invented certain new and useful Improvements in Compound Steam-Engines; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical sectional view of my improved steam-engine. Fig. 2 is a vertical cross-section on line $x-x$, Fig. 1. Fig. 3 is a similar view on line $y-y$, Fig. 1; and Fig. 4 is a perspective view of the slide-valve.

Similar letters of reference indicate corresponding parts in all the figures.

My invention has relation to steam-engines; and it consists in the improved construction, combination, and arrangement of parts of an engine having a cylinder open at one end and provided with two double-acting and one single-acting piston, which at the same time acts as head for the cylinder, as hereinafter more fully described and claimed.

In the accompanying drawings, the letter A indicates the cylinder, which is provided with an outer jacket, B, forming a steam-space, C, around the same, into which the exhaust-steam enters, passing out at the top of the cylinder through the exhaust-pipe D. The upper portion of the inner casing, E, of the cylinder extends above the outer casing, forming a heavy valve-seat, F, through which the several steam channels pass, and upon which the valve G slides. Above and around the valve and valve-seat, which latter extends nearly the entire length of the cylinder, is the steam-chest H, into which the live steam enters through the live-steam pipe I at the top of the steam-chest. Three steam-channels open from the steam-chest through the valve-seat into the cylinder, the one, J, opening at the end of the cylinder, the other, K, one-third of the length of the cylinder from J, and the third, L, one-third of the length of the cylinder from K, and from the open end of the cylinder, thus placing the

port of channel K at equal distances from channels J and L. Two exhaust-channels, M and N, open from the valve-chest, near the ports of channels J and L, into the exhaust-jacket through the valve-seat. Three pistons, O, P, and Q, slide in the cylinder, each sliding in the space between two of the steam-ports, and the two outer ones, O and Q, are connected by two rods, R, provided with the usual cross-heads, S, sliding in guides T, and having connecting rods or pitmen U, which are hinged to two cranks, V, upon the drive-shaft W, while the middle piston, P, is provided with a rod, Y, passing through a central packed aperture, Z, in the piston Q, nearest the open end of the cylinder, and having cross-head a, sliding in guides v, and connecting-rod c, hinged to a crank, d, upon the drive-shaft, diametrically opposite to the two cranks V.

The valve G consists of a flat hollow casing, having downward bent ends which slide upon the valve-seat, forming a longitudinal channel, e, forming recesses f and g in the downward-turned ends, and forming a space, h, between the raised central portion of the body of the valve and the valve-seat. The recesses f and g are of sufficient length to connect, respectively, the ports of the steam-channel J and exhaust-channel M and the steam-channel L and exhaust-channel N, and the recess g, which is at the end of the valve nearest to the open end of the cylinder, is of sufficient length to connect the port of the steam-channels K and L, while the distance between the outer wall of the recess f and that of the recess g is such that when the valve is in its position nearest to the open end of the cylinder the said walls will be outside the ports of steam-channel J and exhaust-channel N, admitting of steam being exhausted at the same time at both ends of the cylinder. Valve G is fastened upon a rod, i, passing out through a packed opening in the end of the steam-chest, and may be operated by any desired valve-operating mechanism.

By the foregoing description, taken in connection with the accompanying drawings, the operation of my engine will be readily understood. When the engine is started, the valve

and pistons are in the position shown in dotted lines in the drawings—*i. e.*, the recesses *f* and *g* connecting the steam and exhaust channels at the ends of the steam-chest, while the 5 space under the raised part of the valve is over the central steam-channel, allowing the live steam passing in through pipe *I* to pass around on both sides of the valve into the cylinder through channel *K*. The action of the 10 steam will now force the pistons *O* and *P* apart, and the valve will slide into the position shown in full lines in the drawings, when the steam 15 will pass out of the space between the pistons *O* and *P*, and will be carried through channels *e* in the valve, and *J* between the head of the cylinder and piston *O*, and through recess *g* between pistons *P* and *Q*, forcing them apart, whereupon the valve returns to its former position, exhausting from channels *J* 20 and *L*, and admitting live steam through channel *K*, thus utilizing the steam first at high pressure and afterward at low pressure by expansion in the same cylinder.

It will also be seen that the valve is balanced by the pressure inside the valve as well 25 as outside, and that the engine may be run at a very high speed without any danger of breakage, steam being continually admitted between the pistons and between the piston and the 30 head of the cylinder when the pistons arrive at the end of their stroke, thus cushioning their force.

Having thus described my invention, I claim and desire to secure by Letters Patent of the 35 United States—

1. A steam-engine having two pistons connected to each other and operating simultaneously, and a third piston operating independently between the two pistons, all in the same 40 cylinder, and having means for admitting high-pressure steam between the central piston and the one of the two outer pistons, and for conveying the same steam to act by expansion between the head of the cylinder and the 45 aforementioned of the connected pistons, and between the central piston and the other of the connected pistons, and for exhausting the latter after it has acted, substantially as and for the purpose shown and set forth.

2. In a steam-engine, the combination of 50

the cylinder *A*, open at one end and having steam-channel *J*, opening at the closed end of the cylinder, steam-channel *K*, opening at one-third of the length of the cylinder from channel *J*, and steam-channel *L*, opening at one-third of the length of the cylinder from channel *K*, with the pistons *O* and *Q*, fastened upon the piston-rods *R* at a distance two-thirds of the length of the cylinder, and the piston *P*, sliding between the two outer pistons, and 55 having rod *Y*, passing out through a central packed opening in piston *Q*, and means for admitting high-pressure steam between pistons *O* and *P*, and for conveying the same steam to act by expansion between the head of the cylinder and piston *O*, and between pistons *P* and *Q*, and for exhausting the same after it has 60 acted, as and for the purpose shown and set forth.

3. In a steam-engine, the combination of the 70 cylinder *A*, open at one end, and having valve-seat *F*, provided with steam-channels *J*, *K*, and *L*, and exhaust-channels *M* and *N*, pistons *O* and *Q*, connected by rods *R*, piston *P*, having rod *Y*, passing out through a packed central 75 opening in piston *Q*, and slide-valve *G*, having longitudinal channel *e*, forming recesses *f* and *g* in its downward-turned ends, and forming space *h* under its raised central portion, as and for the purpose shown and set forth. 80

4. The herein-described steam-engine, consisting of the cylinder *A*, forming space *C*, having exhaust-pipe *D*, valve-seat *F*, having steam-channels *J*, *K*, and *L*, and exhaust-channels *M* and *N*, steam-chest *H*, having live-steam pipe *I*, valve *G*, pistons *O*, *P*, and *Q*, piston-rods *R* and *Y*, having cross-heads *S* and *a*, guides *T* and *b*, connecting-rods *U* and *c*, and drive-shaft *W*, forming double cranks *V* and *d*, all constructed, combined, 85 and arranged as and for the purpose shown and set forth.

In testimony that I claim the foregoing as my own I have hereunto affixed my signature in presence of two witnesses.

MINEHEART BRUNELL.
